INVENTOR
Stanley E. Boynton

UNITED STATES PATENT OFFICE.

STANLEY E. BOYNTON, OF ROCHESTER, NEW YORK, ASSIGNOR TO FITZ-EMPIRE
DOUBLE PIVOT LAST COMPANY, OF AUBURN, MAINE, A CORPORATION OF
MAINE.

LAST.

Application filed January 26, 1920. Serial No. 353,959.

To all whom it may concern:

Be it known that I, STANLEY E. BOYNTON, a citizen of the United States, residing at Rochester, in the county of Monroe and 5 State of New York, have invented certain Improvements in Lasts, of which the following description, in connection with the accompanying drawings, is a specification, like reference characters on the drawings indicating like parts in the several figures.

This invention relates to hinge lasts, that is, lasts comprising a forepart and a heel part, together with a bonding or "hinge" mechanism to facilitate relatively moving 15 these last parts when removing the last from a shoe. This so-called hinge mechanism is frequently not a true hinge, that is, it may not provide for a strictly circular swing about a single fixed pivot, but may provide 20 for a relative movement of any type. In the illustrated embodiment of the invention, the movement is a compound one about a moving center.

The primary mechanical (as distinguished 25 from geometrical) desiderata in a last hinge mechanism are simplicity and strength. The last is also frequently desired to have certain positive or impositive locking characteristics, the provision for which generally detracts from the simplicity (and therefore 30 from the reliability and cheapness) of the construction. It is generally desirable that a last be held in extended position with sufficient rigidity to withstand the operations 35 of machine shoemaking, and often desirable that it be absolutely rigidly so held and, at least, impositively held in collapsed position, to avoid accidents in handling it or to insure that it will not straighten until it is 40 desired to do so.

It is the object of my invention to provide a hinge mechanism for a last which shall be simple, strong and cheap, as well as reliable in operation. An important feature of the 45 invention consists in two hinge members which independently unite the last parts and co-operate with each other to hold the last in a desired position. In the illustrated last a hinge member has a pin connection with 50 one last part and a pivot and slot connection with the other whereby it may move in the last to co-operate with the other hinge member. This connection is also preferably arranged so that the effective length of the

hinge member, herein shown as a link, is not 55 changed by its movement in the last.

These and other features of the invention, including certain details of construction and combinations of parts, will be explained in connection with the accompanying drawings 60 which show a preferred embodiment of the invention selected for illustrative purposes, and then pointed out in the appended claims.

Fig. 1 of the drawings shows the last in 65 extended position.

Fig. 2 shows the last in collapsed position. The last is divided into a forepart 10 and a heel part 12 by a cut of suitable shape. In the last shown in the drawing this cut comprises a substantially vertical cut 14 beginning in the tread face of the last, followed by a forwardly and upwardly extending cut 16, extending to the opening 18, and followed by more or less forwardly sloping cuts 20, 22 in the forepart, and a backwardly 70 sloping cut 24 on the heel part. The forepart is bored for two hinge pins 26, 28 and the heel part for two more hinge pins 30, 32. The upper and lower pairs of these pins are connected by links 34, 36, respectively. 80

The link 34 has a slot 38, substantially arcuate about the center of the pin 26, and an aperture 40 for the reception of an operating tool, as will be described. The link 34 also has a downwardly extending projection 42, having front and rear faces 44 and 46 arranged to co-operate with the rear and front faces 48, 50 respectively, of an upwardly extending lug 52 on the link 36, when the last is in collapsed and extended 90 position, respectively.

These two positions are illustrated in the two figures of the drawing. The combined link and locking member 34 is maintained in operative position by a spring 54 seating 95 against it above the pivot 26, as shown.

In view of the relation of the slot 38 to the pin 26 the movement of the member 34 upon the pin 30 will permit no looseness in the last. The lock in extended position is 100 positive, and is broken by lifting the member 34 by means of some suitable tool in engagement with the hole 40. The angularity of the surfaces 44 and 48 is so adjusted that the lock in collapsed position is impositive, 105 i. e., the lock in collapsed position may be broken by a substantial pressure, whereupon the last will straighten and lock positively.

under the pressure of the spring 54, the angularity of the surfaces 46 and 50 in the last illustrated being so adjusted that the lock, in extended position, is positive and not breakable by pressure. Either lock may be made to work either way by a suitable change in slope of the surfaces 44 and 48, or 46 and 50.

The entire hinge and locking mechanism is thus seen to consist of the two link members and single spring only. It is extremely simple and very strong.

The last is not weakened by additional cutting in order to accommodate the locking mechanism, as is the case in many lasts of the prior art. All of its mechanism can be placed in a single kerf of minimum width.

Having thus described my invention, what I claim as new and desire to secure by Letters Patent of the United States is:—

1. A last comprising a forepart, a heel part, and two rigid hinge members each joining said parts, said members being constructed and arranged to engage each other to hold the last in extended position.

2. A last comprising a forepart, a heel part, and two rigid links each joining said parts, said links being constructed and arranged to engage each other to hold the last positively in extended position.

3. A last comprising a forepart, a heel part, and two link members lying one above the other each uniting said parts, said links being constructed and arranged to co-operate with each other to hold the last in collapsed position.

4. A last comprising a forepart, a heel part, and two links lying one above the other and uniting said parts, said links being constructed and arranged to co-operate with each other to hold the last impositively in collapsed position.

5. A last comprising a forepart, a heel part, and two hinge members each uniting said parts, said members being constructed and arranged to co-operate with each other to hold the last in collapsed position and to hold it positively in extended position.

6. A last comprising a heel part, a forepart, and hinge members joining said parts, one hinge member being constructed and arranged to move in the last independently of its behavior as a hinge member to co-operate with the other hinge member to hold the last parts in a desired relative position.

7. A last comprising a heel part, a fore-

part, and hinge members joining said parts, one hinge member being constructed and arranged to move in the last independently of its behavior as a hinge member to wedge against the other hinge member to hold the last parts in a desired relative position.

8. A last comprising a heel part, a forepart and a hinge link joining said parts, said link having a rotary movement as regards one last part and a combined movement of rotation and translation as regards the other said last part, and a second link joining said last parts.

9. A last comprising a heel part, a forepart and a hinge link joining said parts, said link having a rotary movement as regards one last part, and a combined movement of rotation and translation as regards the other said last part, said link being constructed and arranged to form an inextensible connection between said last parts.

10. A last comprising a heel part, a forepart, and two hinge members uniting said parts, one of said members having a pin connection with one of said last parts and a pin and slot connection with the other of said last parts whereby it may move into and out of co-operation with said other link member to hold the last parts in position.

11. A last comprising a heel part, a forepart, two hinge members each independently uniting said parts and rigid and integral lugs on said members constructed and arranged for interengagement to hold the last in a desired position.

12. A last comprising a forepart, a heel part, and two hinge members uniting said last parts, one of said members having a simple pivotal connection with one last part and a pin and slot connection with the other said last part, the slot being substantially circular around the axis of the said simple pivotal connection, whereby the said one member may be swung into engagement and disengagement with the other said hinge member to hold the last parts in relative position.

13. A last comprising a forepart and a heel part and hinge members joining said parts constructed and arranged to hold the last positively in extended position and impositively in collapsed position.

In testimony whereof I have signed my name to this specification.

STANLEY E. BOYNTON.
